Primary Examiner — Deanna L Pratt(74) *Attorney, Agent, or Firm* — Banner & Witcoff, Ltd.(57) **CLAIM**

The ornamental design for fuel line disconnect pliers, as shown and described.

DESCRIPTION

FIG. 1 is a top, front, right perspective view of fuel line disconnect pliers showing my new design;
FIG. 2 is a front view thereof;
FIG. 3 is a rear view thereof;
FIG. 4 is a right side view thereof;
FIG. 5 is a left side view thereof;
FIG. 6 is a top view thereof; and,
FIG. 7 is a bottom view thereof.

The broken lines in the drawings illustrate portions of the fuel line disconnect pliers that form no part of the claimed design.

1 Claim, 4 Drawing Sheets(56)
